SAFETY RAZOR BLADE

Application filed April 15, 1930. Serial No. 444,380.

This invention relates to improvements in safety razor blades, and, more particularly, to safety razor blades of the double edge type.

5 When using ordinary double edge safety razor blades, the same are mounted in a holder comprising a guard base and a removable clamp head or cap, so as to be clamped between said parts which are of curvilinear 10 shape in cross-section so as to flex the blade about its longitudinal axis. When the blades are thus clamped and flexed, it is not of infrequent occurrence that the blade fractures so as to break off portions or all of the cutting 15 edge. Fractures sometimes occur by reason of a too tight pressure of the clamp head or cap, and sometimes the fractures result from dropping the holder and blade whereby the corners of the holder base or 20 clamp head or both are bent from proper plane, so that when the blade is clamped and flexed therebetween unequal stress is exerted on the corner sections of the blade, which tend to start a fracture at such corner. Such 25 fractures, however caused, usually start at an end of the blade body inward of a cutting edge, and either run throughout the length of the blade body so as to separate the entire adjacent cutting edge therefrom, or the fractures run diagonally to a point along the cutting edge so as to separate a substantial portion of the cutting edge portion from the blade body. In either event the cutting edge 30 portion thus separated is quite likely to be displaced relative to the guard members of the base, so as to work out beyond the same, with risk of producing a dangerous gash in the face of the user, should the fractured condition of the blade not have been discovered before shaving. Another factor contributing to possible fracture of ordinary double edge safety razor blades, is that, owing to the stiffness and temper of the blade body along 35 its longitudinal axis, which is not materially reduced by the longitudinally spaced separate perforations provided to engage the studs of the holder, resistance to flexure is such that strains are set up which tend to render the blades more easily subject to the occurrences of fracture, especially if subjected

to abnormal jars, such as result from dropping.

Having the above matters in mind, it is the object of this invention to provide a novel construction of safety razor blade having means to prevent fractures, if occurring, from running or carrying back through the body of the blade; and, furthermore, to provide a form of stud receiving perforation which, while so engaging the studs of the holder as to securely retain the blade against longitudinal and lateral play in the holder, will at the same time reduce the tension of the blade body along a median longitudinal line, thus tending to permit said blade body to easily flex at such median line with less tendency to set up undue or unequal strains or stresses in the outlying longitudinal half sections thereof, whereby all tendency to fracture under blows or jars is greatly reduced.

An illustrative embodiment of a double edge safety razor blade according to this invention is shown in the drawings, in which:—

Fig. 1 is a large face view of the novel blade of this invention; Fig. 2 is a face view of an ordinary double edge safety razor blade as heretofore commonly used, said view showing a characteristic result of fracture; and Fig. 3 is a face view of the blade according to this invention, showing the manner in which a fracture, if occurring, is prevented from running back through the blade body, and is confined to a limited and small corner portion of the blade.

Similar characters of reference are employed in the above described views, to indicate corresponding parts.

Referring to the drawings, the reference character 5 indicates the blade body, which is made of thin tempered steel. The opposite longitudinal margins of said blade body are ground and honed to provide the usual cutting edges 6 along each side thereof.

Provided in each corner of the blade body 5, inwardly of the adjacent cutting edge and near the end margin of the blade, are perforations 7. Preferably these perforations 7 are of triangular shape, having their bases 7' substantially parallel to the longitudinal axis of

the blade body, and their inner sides 7" more or less parallel to the blade ends. It will be understood, however, that said perforations may be otherwise shaped, the preferred shape described being selected for the reason that it produces a weakened neck 8 at the blade cutting edges which, should fracture occur, will readily break through at such predetermined point, said predetermined point being so located as to lie under a guard tooth of the holder so as not to expose a corner likely to produce scratches on further use of the blade.

In Fig. 2 there is shown a double edge blade *a* of well known common form in which the effect of fracture is illustrated. Usually the break *b* starts at an end of the blade and runs inwardly through the body thereof, sometimes throughout the entire length of the same, but most often in a diagonal line eventually intersecting the adjacent cutting edge. As a result of the break a substantial section *c* of the blade body and a cutting edge thereof is entirely separated therefrom. Such section *c* will either become displaced from the holder so as to present a portion of the cutting edge out of alignment with the holder guard members, with resultant risk of gashing the face of the user, should the break not be discovered before using the razor; or, if the broken section drops out of the holder leave but an unexposed blade portion.

In the novel blade made according to this invention, owing to the provision of the described perforations 7, if, when the same is clamped and flexed in the holder, a fracture begins at the end of the blade, the same, in starting to run longitudinally inward through the blade body, will encounter almost at once the adjacent perforation 7 into which it will extend, with the result that it is blocked thereby from penetrating further into the said body, and thus checked without injury to the adjacent blade edge; or, if the stress to which the fracture is due is great enough, the break will be diverted when the perforation is encountered and caused to extend through the blade edge at a predetermined point, thus merely removing a limited corner area of the blade with minimum reduction of the cutting edge, whereby the latter is substantially preserved for continued use, even after such corner portion is removed. The latter effect is illustrated in Fig. 3 of the drawings, which shows but a small corner section *d* of the blade body removed.

Referring again to Fig. 1 of the drawings, in addition to the novel features already adverted to, a novel form of continuous stud receiving perforation 9 is shown, which continues uninterruptedly throughout the blade body so as to terminate short of the blade ends, whereby two longitudinal blade sections are provided connected by easily flexed median portions 10. Said perforation 9 is

so formed that diagonally and oppositely disposed stud engaging abutments 11 are provided in its margins, whereby the blade holder studs may not only extend through the blade body, but will be so engaged by said abutments 11 as to adequately hold the blade against both longitudinal and lateral displacement. Owing to the continuous formation of perforation, a substantial amount of metal is removed along the longitudinal center of the blade leaving only the median portions 10 at each end thereof to connect the blade sections and to maintain the integrity of the blade body as a whole, with the result that the tension of the blade body along its longitudinal axis is reduced, so that the blade sections may be more readily flexed and, when flexed, reducing the stresses and strains which contribute to the likely occurrence of fractures, as above referred to.

From the above description it will be obvious that the present invention provides a novel form and construction of double edge safety razor blade, wherein tendency to the occurrence of fractures is greatly reduced, and wherein, should fractures occur, the same are controlled and directed so as to effect substantially no material injury to the cutting edges of the blade.

Having thus described the present invention, I claim:-

1. A safety razor blade, comprising a body of thin flexible steel having cutting edges along the opposite longitudinal margins thereof, said body having an uninterrupted central perforation extending along the longitudinal median line thereof, the margins of said central perforation being formed to provide diagonally and oppositely exposed holder stud engaging abutments, said central perforation being adapted to form median portions at the ends of the blade body between the longitudinal sections thereof whereby resistance to flexure of the blade is reduced, said body having additional fracture diverting perforations inward of the cutting edges thereof and respectively adjacent to the blade ends.

2. A safety razor blade, comprising a body of thin flexible steel having cutting edges along the opposite longitudinal margins thereof, said body having an uninterrupted central perforation extending along the longitudinal median line thereof, the margins of said central perforation being formed to provide diagonally and oppositely exposed holder stud engaging abutments, said central perforation being adapted to form median portions at the ends of the blade body between the longitudinal sections thereof whereby resistance to flexure of the blade is reduced, said body having additional fracture diverting perforations of substantially triangular shape located inward of the cutting edges thereof and respectively adjacent

to the blade ends, said perforations having their bases substantially parallel to the longitudinal axis of said blade body, their inner sides substantially parallel to the ends of said blade body, and their apexes directed toward an adjacent cutting edge of said blade body.

3. A safety razor blade, comprising a body of flexible steel having cutting edges along opposite longitudinal margins thereof, said body having fracture diverting perforations of substantially triangular shape located inward of the cutting edges thereof and respectively adjacent to the blade ends.

15 4. A safety razor blade, comprising a body of flexible steel having cutting edges along opposite longitudinal margins thereof, said body having fracture diverting perforations of substantially triangular shape located inward of the cutting edges thereof and respectively adjacent to the blade ends, and said perforations having their bases substantially parallel to the longitudinal axis of said blade body, their inner sides substantially parallel to the ends of said blade body, and their apexes directed toward an adjacent cutting edge of said blade body.

In testimony that I claim the invention set forth above I have hereunto set my hand

30 this 14th day of April, 1930.
